UNITED STATES PATENT OFFICE

163,106

SHOE TREE OR THE LIKE

Trina A. Evans, Philadelphia, Pa.

Application November 16, 1948, Serial No. 149,667

Term of patent 14 years

(Cl. D7—3)

To all whom it may concern:

Be it known that I, Trina A. Evans, a citizen of the United States, residing in Philadelphia, county of Philadelphia, State of Pennsylvania, have invented a new, original, and ornamental Design for a Shoe Tree or the like, of which the following is a specification, reference being had to the accompanying drawing, forming part thereof.

In the drawing:

Fig. 1 is a perspective view of a shoe tree showing my new design;

Fig. 2 is a side elevational view thereof;

Fig. 3 is a top plan view thereof.

I claim:

The ornamental design for a shoe tree or the like, as shown.

TRINA A. EVANS.
